UNITED STATES PATENT OFFICE.

CHARLES H. H. FRENCH, OF HOLLISTER, CALIFORNIA.

PIPE-WRENCH.

SPECIFICATION forming part of Letters Patent No. 395,046, dated December 25, 1888.

Application filed April 24, 1888. Serial No. 271,661. (No model.)

To all whom it may concern:

Be it known that I, CHARLES H. H. FRENCH, a citizen of the United States, residing at Hollister, in the county of San Benito and State of California, have invented new and useful Improvements in Pipe-Wrenches, of which the following is a specification.

My invention is in the nature of improvement in pipe-wrenches, and has for its object to simplify the construction, increase the extent of adjustment, and, in general, to increase the effectiveness of such devices.

With these objects in view my invention consists in the improved construction, arrangement, and combination of parts hereinafter fully described, and afterward specifically pointed out in the claims.

In the drawings, Figure 1 is a view in perspective of a pipe-wrench made according to my invention, adjusted so as to grasp a large pipe, the pipe being shown in dotted lines between the jaws. Fig. 2 is a view in side elevation showing the wrench adjusted to grasp a pipe of much smaller size.

Like letters of reference mark the same parts in both figures.

Referring to the drawings by letter, A and B are the handles. To the handle B, near its upper end, is secured or formed as part thereof a flat box-like or tubular structure, C, through which the handle A passes and which is pivoted on a pin, b, the said pin passing through a lug, a, on the side of the handle A, so as to throw the pivot out of line, as shown in dotted lines in Fig. 2 and full lines in Fig. 1.

In the tubular portion C of the handle B is a notch, D, in which rests and turns a hand-nut, E, on the threaded end f of the curved jaw F, which forms the outer jaw of the wrench and is of the form of the ordinary "cant-hook." The main body g of this jaw F is substantially rectangular in section and

fits and slides in the tubular portion C of handle B.

H is the inner jaw of the wrench, formed upon the handle A, and having a curved serrated outer end, h, as clearly shown.

The operation of my invention is as follows: The parts being adjusted to fit the particular size of pipe, by turning the nut E, and thus causing the jaws F to move outward or inward, as desired, the jaws F and H are spread apart. By moving the handles A and B apart the hook-jaw F is passed over the pipe, and by pressing the handles together the serrated curved end of the jaw H is brought against the pipe, which is at once securely grasped, so that it is well nigh impossible for it to turn in the wrench.

What I claim, and desire to secure by Letters Patent of the United States, is—

1. In combination, the handles A and B, pivoted together, the handle B being provided with the tubular portion C, through which the handle A passes, and the jaw F, provided with the hook end and adjustable in the tubular portion C of handle B in a line substantially parallel with handle A, as described.

2. The combination of handle B, having tubular portion C projecting from one side thereof, the sliding jaw F, adjustable therein, and the handle A, extending through the tubular portion and provided with a lug through which the pivot-pin passes, which secures it to handle B, the outer end of said handle A forming a jaw, H, with curved serrated end h, as set forth.

In testimony whereof I affix my signature in presence of two witnesses.

CHAS. H. H. FRENCH.
